UNITED STATES PATENT OFFICE.

JOSEPH WORCESTER, OF NEWPORT, KENTUCKY.

IMPROVEMENT IN GLOBE-COCKS.

Specification forming part of Letters Patent No. **55,756**, dated June 19, 1866.

To all whom it may concern:

Be it known that I, JOSEPH WORCESTER, of Newport, Campbell county, State of Kentucky, have invented certain new and useful Improvements in Valves; and I do hereby declare the following to be a full, clear, and exact description thereof, reference being had to the accompanying drawings, making part of this specification.

My invention consists of a valve and attachments applicable for a steam-valve, water-valve, or mud-valve, the valve being so connected that it can be rotated on its seat from the outside for grinding, cleaning, or other purposes independent of the opening or closing mechanism.

In the accompanying drawings, Figure 1 is an axial section of a globe-valve embodying my invention. Fig. 2 is a similar view of a mud-valve.

A is the shell of an ordinary globe-valve, provided with the usual seat B. C is the valve rigidly connected to the stem and hand-wheel D E, the stem working through an ordinary stuffing-box, F.

The common screw-threaded stem G is provided with a circular button, H, which is fitted into a recess in the valve and kept in place (capable only of rotation) by means of the in-

side screw-thimble, I. The valve-stem G is provided with stuffing-box J and hand-wheel K, the wheel serving to operate the valve in opening and closing.

Ordinarily the simple rotation of the valve on its seat will clear away any foreign matter that may have rested on the bearing-surfaces and prevented a tight joint. This can be effectually accomplished by the simple rotation of the hand-wheel E.

For the purposes of grinding pressure can be applied by hand-wheel K and screw-stem G, the necessary rotation being accomplished through hand-wheel E and stem D.

Fig. 2 exhibits the application of my improvements to the mud-valve, the same letters of reference applying to both figures.

I claim herein as new and of my invention—

The valve C, adapted to rotate, in the manner substantially as described, on the stem G, and provided with a rigid stem, D, operated from the outside, in the manner and for the purpose specified.

In testimony of which invention I hereunto set my hand.

JOSEPH WORCESTER.
